Primary Examiner — Paula Greene(74) *Attorney, Agent, or Firm* — Saidman DesignLaw Group, LLC(57) **CLAIM**

The ornamental design for a microphone mount, as shown and described.

DESCRIPTION

FIG. 1 is a top perspective view of a microphone mount showing our new design;

FIG. 2 is a bottom perspective view thereof;

FIG. 3 is another top perspective view thereof;

FIG. 4 is another bottom perspective view thereof;

FIG. 5 is a front view thereof;

FIG. 6 is a rear view thereof;

FIG. 7 is a right side view thereof;

FIG. 8 is a left side view thereof;

FIG. 9 is a top view thereof; and,

FIG. 10 is a bottom view thereof.

The dashed broken lines illustrate structure or features which form no part of the claimed design.

The drawings include CAD lines which represent contour, not surface ornamentation.
